GAS FLAME COMBINATION COVER PLATE AND SIMMERER

Lena L. Troutman, 418 W. Monroe St.,
Salisbury, N.C. 28144

Filed June 30, 1969, Ser. No. 18,342

Term of patent 14 years

Int. Cl. D7—02

U.S. Cl. D81—25

FIG. 1 is a top plan view of a gas flame combination cover plate and simmerer embodying the features of my new design.

FIG. 2 is a side elevational view thereof.

FIG. 3 is a bottom plan view as viewed on line 3—3 of FIG. 2.

FIG. 4 is a sectional view as viewed on line 4—4 of FIG. 1.

This application is a division of my copending application Ser. No. D. 13,161, filed Aug. 16, 1968.

I claim:

The ornamental design for a gas flame combination cover plate and simmerer, substantially as shown and described.
